(57) **CLAIM**

The ornamental design for a stand mixer as shown and described.

DESCRIPTION

FIG. 1 is a top perspective view of a stand mixer showing our design;

FIG. 2 is a top, front perspective view thereof;

FIG. 3 is a bottom, rear perspective view thereof;

FIG. 4 is a front view thereof;

FIG. 5 is a rear view thereof;

FIG. 6 is a side view thereof;

FIG. 7 is an opposite view thereof;

FIG. 8 is a top view thereof; and,

FIG. 9 is a bottom view thereof.

The evenly dashed broken lines illustrate portions of the stand mixer that form no part of the claim. The dash-dot broken lines define the boundaries of the claim and form no part thereof.
